DESIGN FOR AN ARCHERY BOW

Philip V. Leivo and Albin J. Herek, Bay City,
Mich., assignors, by mesne assignments, to
Metal-Lite Products Co., Bay City, Mich.

Application July 31, 1946, Serial No. 132,119

Term of patent 14 years

(Cl. D34—15)

To all whom it may concern:

Be it known that we, Philip V. Leivo and Albin J. Herek, both citizens of the United States of America, residing at Bay City, in the county of Bay and State of Michigan, have invented a new, original and ornamental Design for Archery Bows, of which the following is a specification, reference being had to the accompanying drawing, forming part thereof.

In the drawing:

Fig. 1 is a top, plan view of our archery bow.
Fig. 2 is an edge-elevational view thereof.

Fig. 3 is an enlarged, fragmentary, side-elevational view showing the center section of the bow.

We claim:

The ornamental design for an archery bow, as shown.

PHILIP V. LEIVO.
ALBIN J. HEREK.
